UNITED STATES PATENT OFFICE.

LIPA POLINKOWSKY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 5, 1919. Serial No. 294,708.

To all whom it may concern:

Be it known that I, LIPA POLINKOWSKY, a citizen of Russia, residing at New York, in the county of New York and State of New York, have invented certain new and useful Improvements in Telephone-Exchange Systems, of which the following is a full, clear, concise, and exact description:

This invention relates to telephone systems employing machine switching apparatus for setting up connections between subscribers' lines.

More particularly, it relates to a machine switching telephone system in which party line working is involved, the several subscribers' stations on a party line being equipped with calling and switch-controlling devices whereby a calling subscriber may control the operation of automatic switches in the exchange to extend his line into connection with any other subscriber's line. Further, means are provided at each substation whereby a calling subscriber on a party line, desiring to hold conversation with another subscriber on the same line, may so control the operation of the automatic switching apparatus at the exchange that a talking connection is established between the calling and called substations on the same party line.

An object of this invention is the provision, in addition to the regular line finders and selectors at the exchange used in establishing a connection between two different subscriber's lines, of a plurality of special line finders which may be taken for use to complete a talking connection whenever a subscriber on a party line desires to converse with another subscriber on the same party line.

A feature of invention, in a system of this character employing special line finders for revertive calls, consists in the arrangement of the line relays such that the act of a calling subscriber in initiating a regular call causes the operation of an ordinary line finder, whereas the act of initiating a revertive call is without effect to start such finder, but serves instead to initiate the operation of another finder used especially for revertive connections.

A further feature is that by the use of

these special line finder switches for revertive calls it is not necessary for the calling subscriber to manipulate his calling device 55 to set up selector and connector switches in the exchange, the complete connection being established by the line finder, and talking battery supplied to the line.

A further feature consists of a source of 60 ringing current associated with the special finders for revertive calling, which when one of such finders is appropriated may be operated to apply the proper character of ringing current back upon the line, thereby 65 ringing the bell of the called substation.

A still further feature of the invention resides in an automatic release mechanism provided in common to a plurality of finder switches, and particularly applicable to the 70 above described type of finders for revertive calling, which becomes effective at the proper time to release any finder switch that has been taken for use; but which due to the subscriber's abandonment of the call, an 75 irregular manipulation of the substation apparatus, or for any other reason has not completed its regular operation.

Such other and further features as are contemplated by the present invention will 80 become clearly apparent from the following description and appended claims.

In the drawing, which forms a part of this application, Fig. 1 shows a party line having four substations thereon, and terminating in the exchange in the multiple terminals or final selectors, the ordinary line finders and the special line finders used for the purpose of making revertive calls.

Fig. 2 shows in detail the circuit arrangement of one of the special line finders. There is also shown a release mechanism adapted to be associated with a plurality of line finders.

It is believed that the invention will be 95 best understood from a description of the operation of the system in which the same is embodied.

Referring to the drawings, each substation on the party line is provided with the usual equipment including the transmitter, receiver, calling dial, ringer, etc. In addition, there is further provided a key 292 for use in making revertive calls, and additional

condensers 294 and 295 and a key 296 to be used for revertive ringing. The party line is connected in the exchange to four sets of terminals such as 270, 271, 272 and 273 in final selective switches. By arranging these terminals in two separate groups of final selectors, each substation on a party line may have a separate number in the exchange which enables the selection of a proper kind of ringing current. The party line also appears in terminals 210, 274 and 276 of an ordinary first line finder such as that diagrammatically illustrated at 277, and further in the terminals 250, 258 and 275 of special line finder switches such as the one shown in detail in Fig. 2 used only when a revertive call is made. Each subscriber's line is provided with two line relays 201 and 202. Relay 201, when operated, serves to start the operation of idle first line finders when a call is made from one subscriber's line to another subscriber's line. Relay 202 is differentially wound and operates only in response to a definite manipulation of the substation apparatus for making a revertive call to start in operation the special line finder switches.

Assume first that a subscriber on the party line shown desires to converse with the subscriber at substation 285 on another line which may be either a party line or an ordinary subscriber's line. On removing the receiver from the switchhook, a circuit is established from battery through the right-hand winding of line relay 202, back contact and outer armature of cut-off relay 207, over the lower side of the line, through keys 292 and 296, dial 293 and thence over the switchhook to the other side of the line and returning over the inner armature and contact of relay 207, through the left-hand winding of relay 202, winding of relay 201 to ground. Current flowing in this circuit is without effect to operate the differential relay 202. Relay 201, however, attracts its armature and closes a circuit from battery, through the inner windings of starting relays 204, over the armature and contact of relay 201, to the terminal 210 of all regular first line finder switches having access to the group of lines to which the calling line belongs, thus placing a selectable condition upon such terminals. The armatures of relays 204, by closing on their contacts, complete a circuit in the well-known manner for the power magnets of all idle first line finders such as the line finder 277, which thereupon begin to move in search of the calling line. Line finder 277 on finding the terminals of the calling line, operates to initiate the movement of a second line finder 278 which extends the connection to a selector 279. The subscriber then manipulates his dial 293 to further extend the connection over selector 279 and final selector 280 to

the called line. The finder and selector switches used in establishing a connection between subscribers' lines may be of any approved type such as the switches disclosed in the patent to Polinkowsky No. 1,193,053, patented August 1, 1916, and need not be described in detail herein.

It will now be assumed that it is desired to establish a substation on the party line, such as the lowermost one in Figure 1, with one of the other three substations on the same party line. The subscriber first operates his revertive calling key 292 and then removes the receiver from the switchhook. When the key 292 is depressed, a circuit is completed from battery, through the right-hand winding of relay 202, contact and outer armature of relay 207, over the lower side of the line to ground at the contact of key 292. Current flowing in this circuit serves to energize the differential relay 202 which attracts its armature and completes a circuit from battery, through the right-hand winding of said relay, contact and outer armature of relay 207, armature and contact of relay 202 to ground through the winding of starting relay 203. Relays 202 and 203 are thus energized in series and relay 201 being shunted, does not operate when its circuit is closed by the release of the revertive calling key 292. The regular line finders are therefore not started in operation. Relay 203 completes a circuit from battery, over its right-hand armature and contact of relay 203 to place a selectable potential upon the terminals 250 of the special line finder switches. A circuit is also closed from ground, over the armature and contact of relay 203, armature and back contact of test relay 212, through the winding of power magnet 211 to battery and ground at the sequence switch contact 215 bottom. This circuit being multiplied to the power magnets of all finders in the group, such finders as are idle at this time will be started to search for the calling line. The brush carriages rotate, and the first finder arriving upon the terminal 250 completes a circuit from battery, through the armature and contact of relay 203, terminal 250, through the right-hand high resistance winding of test relay 214, to ground at contact 216 of sequence switch 220. Relay 214 operates and closes a circuit in parallel to its right-hand winding which includes the low resistance left-hand winding of such relay and the second test relay 212. The low resistance of this circuit so reduces the potential on terminal 250 as to render the calling line non-selectable to other finders. Relay 212 by operating, opens the circuit for the power magnet 211 which brings the brush carriage to rest. A circuit is also closed over the front contact of relay 212, sequence switch contact 217

bottom, to drive the sequence switch 220 out of position 1 and into position 4.

The sequence switch contact 216, in passing out of position 1, opens the energizing circuit of the high resistance winding of test relay 214. In position 3 of sequence switch 220, a circuit is closed from battery, through the left-hand winding of relay 222, sequence switch contact 217 top, front contact and armature of relay 212 to ground at the left-hand armature of relay 203. Relay 222 operates and closes a circuit from ground, over sequence switch contact 216 top, armature and front contact and right-hand winding of relay 222, terminal 258, through the winding of cut-off relay 207 to battery and ground. Cut-off relay 207 operates and relay 222 remains energized in this circuit. The cut-off relay, by operating, opens the circuit of line relay 202 and starting relay 203 which are thereby deenergized. Other searching line finders are brought to rest at this time.

When sequence switch 220 reaches position 4, a circuit is completed from battery, through the secondary winding of the dial tone coil 224, contact 213 top, right-hand armature and back contact of relay 226, back contact and left-hand armature of relay 227, over the lower side of the line, through the substation loop and returning over the upper side of the line through the right-hand armature and back contact of relay 227, left-hand armature and back contact of relay 226, sequence switch contact 235 top, through the winding of the stepping relay 229 to ground. Relay 229 energizes and closes a circuit from ground, through its armature and front contact, armature and back contact of relay 223, through the winding of relay 231 to battery and ground. Relay 231, by attracting its armature, closes a circuit over contact 219 top to drive the sequence switch 220 out of position 4, through positions 5 and 6 into position 8. On reaching position 8, contact 215 closes an energizing circuit for relay 223 including the armature and back contact of relay 232.

The register 100, individual to the finder switch and which is operated under the control of the calling substation to apply ringing current of the proper character back upon the calling line, is now moved out of position zero by a circuit from battery, through the winding of register 100, contact 228 bottom, contact and armature and left-hand winding of differential relay 239, front contact and armature of relay 223, to ground at the armature of relay 229. The register 100, leaving position zero, closes a circuit to ground at its local contact 101, thereby shunting the left-hand winding of differential relay 239, so that this relay is now energized in series with the retardation coil 233. Register 100 moves into position 1

where it comes to rest. The primary winding of the dial tone coil 224 is connected over contact 108 with the interrupter 245. The calling subscriber hearing the dialing tone, operates his dial 293 for one digit corresponding to the designation of the substation wanted on the same party line. At the first interruption, the line relay 229 deenergizes and opens the circuit through the right-hand winding of relay 239, which also deenergizes. When the line is again closed at the end of the first impulse, the circuit for the right-hand winding of relay 239 is closed and at the same time the above traced circuit including sequence switch winding 100 and the left-hand winding of differential relay 239. Relay 239 remains inactive and the register 100 starts from position 1. On leaving position 1, the left-hand winding of relay 239 is shunted at the local contact 101, and relay 239 thereby energizes. At the same instant, a circuit is completed from battery, through the winding of relay 237, contact 228 bottom to ground at the local contact 101. Relay 237 closes at its armature a circuit to ground for the right-hand winding of relay 239, independent of the ground at relay 229. This insures that the relay 239, once operated, will retain its armature until the register 100 has taken a full step and opened the circuit for relay 237 which occurs as soon as said register reaches position 2. With the relay 237 deenergized in position 2, when the subscriber's line is open on the second impulse, the right-hand winding of relay 239 deenergizes once more and said relay releases its armature. This operation continues and the register 100 advances one step for each interruption caused by the calling subscriber's dial. Each time the relay 229 retracts its armature, a momentary circuit is closed for relay 234, over sequence switch contact 236, but this relay, being constructed to energize slowly, does not operate at this time. However, on the last interruption caused by the subscriber's dial, the line is opened for a comparatively longer interval which enables the relay 234 to become energized. A circuit is thereupon completed from ground, over the armature and contact of relay 234, sequence switch contact 243 bottom, through the right-hand winding of relay 232 to battery and ground. The energization of relay 232 closes a circuit from battery, through the winding of sequence switch magnet 220, armature and back contact of relay 231, contact 218 top, left-hand winding, front contact and armature of relay 232, to ground, causing said sequence switch to move into position 11. Before sequence switch 220 can reach position 11, relay 229 will have been energized in series with the line for a sufficient time to permit the deenergization of relay 234. Relay 234, in releasing its armature, opens

the circuit for the right-hand winding of relay 232 and the left-hand winding of this relay being short-circuited by the local contact 221 between positions 8 and 11, such 5 relay will deenergize and open the above traced circuit which started sequence switch 220 out of position 8.

The calling subscriber now depresses the revertive ringing key 296 which brings the 10 small condenser 294 in series with his telephone and also opens the circuit of the substation to the flow of direct current. The line circuit, being thus opened, relay 229 deenergizes and at its back contact closes a 15 circuit for relay 234 over sequence switch contact 236 top, which in turn energizes and closes a circuit over sequence switch contact 243 top for the energization of the right-hand winding of relay 232. Relay 232 20 again energizes and closes the above traced circuit including sequence switch contact 218 top and the armature of relay 231 to drive sequence switch 220 out of position 11 and into position 12.

25 As was previously mentioned, the terminals of party lines are arranged in two groups of final selectors in the exchange. By this arrangement, when a call is established between two different lines, which 30 operation involves the use of a final selector switch, these selectors, by connecting the called line over one or another set of terminals in which it appears dependent upon the designation of the party desired, are effective to apply ringing current of the proper character to ring the bell of the called substation. For this purpose, alternating ringing current superimposed upon direct current of different polarities may be used 35 40 for ringing the desired bell. Since each final selector is provided with 200 terminal sets, the four stations of the party lines could have numbers varying only in their hundreds digit.

45 When a revertive call is made and only one digit is dialed for selecting the proper kind of ringing current this digit may correspond to the hundreds digit of the party line number. The register 100 is arranged 50 to provide the required connection for revertive ringing in positions 6, 7, 8 and 9, which correspond to the dialing of numbers 4, 3, 2 and 1. According to the position in which register 100 stands, either the relay 55 60 65 70 75 80 85 90 95 100 105 110 115 120 125 130 226 or relay 227 is energized in a circuit over the back contact of relay 230 and sequence switch contact 238 top. If the digit 1 or 2 has been dialed and the register 100 is in position 9 or 8, the relay 227 will be energized. This circuit is traceable from battery, through the winding of said relay, contact 103, back contact and armature of relay 230, contact 238, to ground, whereas, if the digit 3 or 4 has been sent and the register stands in positions 7 or 6, the relay

226 is energized in a circuit from battery, through the winding of said relay, sequence switch contact 107, back contact and right-hand armature of relay 230, contact 238 top to ground.

An alternating ringing current superimposed upon direct current is sent over the party line. In case the digit 1 or 2 was sent, and relay 227 energized, the ringing circuit leads from the alternating current source, over either the contact 109 or 110 dependent upon the digit, front contact and left-hand armature of relay 227, to the lower side of the line, through the ringing relays 297, 298 and 299 of the other three substations, back over the upper side of the line, through the right-hand armature and front contact of relay 227, winding of relay 240 to ground at the left-hand armature of relay 230. Only the ringer at the desired station is operated. In case the digits 3 or 4 were sent, and relay 226 energized instead of relay 227, the ringing circuit is traceable from the alternating current source, through battery, over the contact 100, 109 or 110, dependent upon the digit, front contact and left-hand armature of relay 226, right-hand armature and back contact of relay 227, over the upper side of the line, through the ringing relays 297, 298 and 299, and returning over the lower side of the line to the armature and back contact of relay 227, right-hand armature and front contact of relay 226, through the relay 240 to ground. By the ringing arrangement above described, the ringer at any one of the four substations may be selected and rung to the exclusion of the ringers at the remaining substation. When the receiver at the called substation is removed from the switchhook, the resistance in series with the ringing control relay 240 being reduced, said relay becomes energized and closes a circuit from battery, through the right-hand winding of relay 230 to ground at the armature of relay 240. Relay 230 closes a locking circuit over its right-hand winding to ground at the sequence switch contact 238 top, and also opens the circuit of relay 240 and either releases relay 226 or 227 as the case may be. The ringing operation is thereby terminated. The talking circuit is now completed and battery furnished to the line, through the winding of relay 231, sequence switch contact 213 bottom, right-hand armature and back contact of relay 226, back contact and left-hand armature of relay 227, over the line and returning by way of the right-hand armature and back contact of relay 226, sequence switch contact 235 bottom, through the retardation coil 247 to ground. Relay 231 energizing closes a circuit over sequence switch contact 219 top to drive sequence switch 220 out of position 12 and through the intermediate positions, coming to rest in position 18. A circuit is

provided for register 100 including contact 102 bottom and contact 238 bottom to move said register into its zero position.

After the conversation is completed and the receivers are replaced on the hooks at both substations, the relay 231 deenergizes and closes a circuit including sequence switch contact 219 bottom, to drive sequence switch 220 into position 1. On leaving position 18, contact 216 opened the above traced holding circuit for relays 222 and 207, which thereupon, deenergize. The apparatus is now restored to normal ready to be operated on the incoming of another call.

In order to make the switches in the exchange independent of an erroneous manipulation of the substation apparatus, the special line finders used for revertive calls have associated therewith an automatic release mechanism, which is common to a plurality of such finders. This mechanism is so arranged that any line finder which has been started in operation by erroneous actuation of the substation equipment will be automatically restored to normal after a reasonable time has elapsed. For instance, the calling subscriber may hold the revertive calling key 292 depressed for an unreasonably long time or he may abandon the call

after having once depressed said key without removing the receiver from the switchhook. Relay 229, which depends for its energization upon a closure of the line circuit, would not be operated and consequently, sequence switch 220 would not be driven out of position 4. To avoid the line being held busy in this manner, the common release mechanism including a sequence switch 260 is provided to insure the restoration of all finders improperly moved from their normal position. When the sequence switch 220 of any one of the special line finders to which the automatic release mechanism is common reaches position 4, a circuit is completed from battery, through the winding of relay 262, contact 242 of sequence switch 220 to ground. Relay 262 energizes provided sequence switch 220 does not pass immediately to position 8, as it would during a normal operation, and connects the relay 264 to an interrupter 269. Each time the interrupter is closed, relay 264 operates and closes a circuit for sequence switch 260 over the right-hand armature and front contact of relay 262, armature and back contact of relay 262, armature and back contact and right-hand winding of relay 268 to ground.

The relay 268, being differential, remains deenergized until sequence switch 260 closes a short circuit at the local contact 261 for the right-hand winding of relay 268. Relay 268 now energizes and opens the circuit traced for sequence switch 260 which is arrested as soon as it reaches position 2. When the interrupter opens the circuit of

relay 264, this relay together with relay 268, deenergizes and the circuit for sequence switch 260 is again prepared. Each time the sequence switch 260 passes from positions 4 to 7, 10 to 13 or 16 to 1, a circuit is temporarily closed over sequence switch contact 265, sequence switch contact 236 bottom to cause the energization of relay 234. Relay 234 attracts its armature and closes a circuit from ground, over its armature and contact, sequence switch contact 243 top, which it will be remembered is in position 4, left-hand winding, armature and contact of relay 239, contact 228 top, armature and back contact of relay 231, through the winding of sequence switch magnet 220 to battery and ground. Sequence switch 220 moves into position 5, and on closing its local contact between positions 4 and 5 short-circuits the left-hand winding of differential relay 239 which energizes and opens the circuit traced for sequence switch 220 until relays 239 and 234 are again deenergized. Relay 262 remaining energized over contact 242 in position 5 of sequence switch 220, sequence switch 260 is advanced at each closure of the interrupter 269 from one position to another until contact 265 is again closed in position 11 of sequence switch 260. Relay 234 is again energized and sequence switch 220 is moved out of position 5 and into position 6 as above described. After contact 265 is closed for a third time when sequence switch 260 arrives in position 17, the sequence switch 220 is moved out of position 6 and into position 8.

It may happen that sequence switch 220 reaches position 4 just before contact 265 closed, due to a sequence switch of another line finder being held in a position in which relay 262 is energized. Sequence switch 220 may therefore move over position 4 immediately, but the sequence switch is detained in its 5th or 6th positions for a reasonable length of time to enable the calling subscriber to remove the receiver from the hook and release the key 292. When the sequence switch 220 leaves position 17, relay 262 remains deenergized and said sequence switch stops when it reaches position 1.

It may further happen that the called party does not reply, whereas the calling subscriber while holding the key 296 depressed would give up the call and restore the receiver to the switchhook before releasing the ringing key. In such a case the line would be opened at the switchhook contact before it would close at the key 296 and consequently the ringing control relay 240 remains deenergized. Sequence switch 220 again provides a connection to the common release equipment so that said sequence switch is at given time intervals advanced over its positions 12, 13, 14, 15, 16 and 17, whereby the ringing of the called

station continues for a reasonable length of time, after which sequence switch 220 moves into position 18. Since the party line is open, relay 231 is deenergized and consequently a circuit is completed over the armature and right-hand contact of said relay to ground at the sequence switch contact 219 bottom to drive the sequence switch 220 out of position 18 and into its normal position 1. In restoring the ringing key 296, a calling subscriber is also enabled to give up the ringing but may continue to wait for a reply from the called subscriber.

If none of the sequence switches corresponding to the sequence switch 220 are in positions 4 to 7, or 12 to 17, relay 262 is deenergized and a circuit is established to drive the sequence switch 260 into either one of its three starting positions 1, 7 or 13. This circuit includes the right-hand armature and back contact of relay 262 and sequence switch contact 267.

The common release mechanism is also capable of releasing the finder switch where two finders have stopped on the terminal of the same calling line. Assuming that two finders reached the terminals of the calling line at the same time, two test relays 214 might become energized in parallel over the right-hand high resistance windings. Upon the sequence switches 200 of such finders moving out of position 1, and consequently, upon the opening of the circuit of the right-hand high resistance windings of the test relays 214, the current flowing in parallel through the circuits including the left-hand low resistance windings of relays 214 and the winding of relays 212 would be insufficient to maintain the energization of both sets of these relays. Consequently, the test relay 212 of one of such line finders would be deenergized immediately upon the sequence switch 220 leaving position 1. Therefore, upon the sequence switch 220 passing through position 3, relay 222 is not energized. Instead, however, a circuit is completed from battery, through the winding of relay 227, left-hand winding of relay 230, back contact and armature of relay 222, sequence switch contact 216 top to ground. Relay 229 and consequently relay 231, are maintained deenergized due to the energization of relay 227, and the sequence switch 220, under the control of the common release mechanism, passes through its cycle of operation as above described. The connecting circuit of the line finder being held open at the contacts of relay 227, and the register 100 remaining in position zero, no interference is caused with the party line during the restoration to normal of a finder switch which has thus been improperly operated.

What is claimed is:

1. In a telephone system, a subscriber's

line, a pair of automatic switches having access to said line for establishing telephone connections, two line relays for said line, one of which is differentially wound, said relays being individual respectively to said automatic switches, means at the substation of said line controlled by the subscriber in the act of initiating a call for selectively operating either of said relays, means responsive to one of said relays for operating the corresponding switch, and means responsive to the other relay for operating the other of said switches.

2. In a telephone system, a subscriber's line, a pair of line finder switches having access to said line, two line relays one of which is differential, said relays being individual respectively to said finders, means under the control of the subscriber in initiating a call for selectively operating either of the line relays and for rendering the other relay inoperative, means responsive to the operation of one of said relays for operating one of the finder switches, and means responsive to the operation of the other of said relays for operating the other finder switch.

3. In a telephone system, a party line, another line, an automatic switch responsive to the initiation of a call on said party line, means cooperating with said switch for establishing a connection between said lines, a second automatic switch responsive to the initiation of a call on the party line for making connection with said party line, and means under the control of the subscriber in initiating a call on the party line for selecting either of said automatic switches for use.

4. In a telephone system, a party line, calling transmitters at the substations on said party line, ringing devices at said substations, another line, selective switches for interconnecting said lines, line finders for automatically extending said party line to the selective switches, a group of special line finders for establishing a telephone connection between two substations on said party line, means under the control of the subscribers in initiating a call on the party line for selecting either said first mentioned finders or said special finders, a source of ringing current associated with the special finders, and means under the control of said calling transmitters for applying said source to the party line to operate the ringing device at a called substation thereon.

5. In a telephone system, a subscriber's line, two groups of automatic switches, said switches being responsive to the initiation of a call on said line to establish a telephone connection, means under the control of the subscriber for selecting for use the switches of either group, a release mechanism for the switches of one of said groups, and means operative under the control of said mecha-

nism for releasing any switch of such group that has been started in operation.

6. In a telephone system, a subscriber's line, two groups of automatic switches, said 5 switches being responsive to the initiation of a call on said line, to establish a telephone connection, means under the control of the subscriber for selecting for use switches of either group, a release mechanism common 10 to the switches of one of said groups, and means operative under the control of said mechanism at the end of a definite time interval after any of such switches have been started in operation for restoring the same 15 to normal.

7. In a telephone system, a line finder switch, a telephone line having a plurality of substations thereon, said line appearing in terminals of the finder switch, means 20 responsive to the act of initiating a call at one of said substations for operating the finder switch to make connection with said line, a talking battery for supplying current for the talking connection between said substations, and means at the finder switch individual thereto and controlled over the line after said switch has operated for connecting said battery to said line.

8. In a telephone system, a line finder switch, a telephone line having a plurality of substations thereon, means responsive to the act of initiating a call at one of said substations for operating said finder, an auxiliary controlling switch for said finder, a 35 talking battery for supplying current for the talking connection between calling and called substations on said line, and means controlled by said auxiliary switch for connecting the talking battery to said line.

9. In a telephone system, a party line, a line finder switch, means responsive to the initiation of a call on said party line for operating said finder, a source of ringing current, and means at said finder switch controlled by a calling subscriber for variably connecting said source of current to the party line to selectively signal the substations on said line.

10. In a telephone system, a party line, 50 a line finder switch, means responsive to the initiation of a call on said party line for operating said finder, a plurality of sources of ringing current of different character, and means at said finder switch controlled by a calling subscriber for variably connecting said sources of current to the party line to selectively signal the substations on said line.

11. In a telephone system, a party line, 55 a line finder switch, calling transmitters at the substations on said line, means responsive to the initiation of a call on the party line for operating said finder, a source of ringing current, and means at said finder switch controlled by the calling transmitters

for variably connecting said source of current to the party line to selectively signal the substations on said line.

12. In a telephone system, a party line, calling transmitters at the substations on 70 said line, means responsive to the initiation of a call on the party line for operating said finder to establish a talking connection between two substations on said line, a source of ringing current, a register at the said 75 finder switch, means controlled by said transmitters for variably setting said register, and means dependent upon the setting of said register for variably connecting said source of current to the party line 80 to selectively signal the substations on said line.

13. In a telephone system, a party line, calling transmitters at the substations on said line, ringing devices at said substations, another line, selector switches for interconnecting said lines, line finders for automatically extending said party line to the selective switches, special line finders for establishing a telephone connection between 90 two substations on said party line, means under the control of the subscriber in the act of initiating a call on the party line for selecting either said first mentioned finders or said special finders, a source of ringing current, a register device individual to each of said special finders, means controlled by said calling transmitters for variably setting said register devices, and means dependent on the setting of said registers for variably connecting said source of ringing current to the party line to selectively operate said ringing devices.

14. In a telephone system, a party line, calling transmitters at the substations on 95 said party line, ringing devices at said substations, another line, selective switches for inter-connecting said line, a line finder for automatically extending said party line to the selective switches, a special line finder for establishing a telephone connection between two substations on said party line, means under the control of the subscribers 100 in initiating a call on the party line for selecting either said first mentioned finder or said special finder, a source of ringing current associated with the special finder, means under the control of said calling transmitters for applying said source of current to the party line to operate the ringing device at a called substation thereon, a talking battery for supplying current for the talking connection between two substations on the party line, and means at said special 110 finder switch for connecting said talking battery to the party line.

15. In a telephone system, a party line, 115 a line finder switch, calling transmitters at the substations on said line, means responsive to the initiation of a call on the party line for operating said finder, a source of ringing current, and means at said finder switch for connecting said talking battery to the party line.

In witness whereof, I hereunto subscribe my name this 29th day of April A. D., 1919.

LIPA POLINKOWSKY.
